(Cl. D30—1)

To all whom it may concern:

Be it known that I, William B. Winslow, a citizen of the United States, residing at Barrington, in the county of Cook and State of Illinois, have invented a new, original, and ornamental Design for an Air Pistol of which the following is a specification, reference being had to the accompanying drawing, forming part thereof.

Fig. 1 is a left side view of an air piston showing my new design;

Fig. 2 is a top view;

Fig. 3 is a right side view;

Fig. 4 is a front view; and

Fig. 5 is a rear view thereof.

I claim:
The ornamental design for an air pistol, as shown.

WILLIAM B. WINSLOW.
